Term of patent 14 years

(Cl. D85—2)

To all whom it may concern:

Be it known that I, Carl A. Sundell, a citizen of the United States and a resident of the city of Muskegon, in the county of Muskegon, State of Michigan, have invented a new, original, and ornamental Design for a Combination Chalk Holder and Ash Tray or the like, of which the following is a specification, reference being had to the accompanying drawings, forming a part thereof, in which

Fig. 1 is a plan view of a combination chalk holder and ash tray or the like showing my new design.

Fig. 2 is a side elevational view thereof; and

Fig. 3 is a right hand end view of Fig. 2.

I claim:
The ornamental design for a combination chalk holder and ash tray or the like, as shown.
CARL A. SUNDELL.
